UNITED STATES PATENT OFFICE.

JOHN HARDMAN, OF NEW YORK, N. Y.

DESIGN FOR AN ORNAMENTAL PANEL FOR PIANOS.

SPECIFICATION forming part of Design No. 17,729, dated September 20, 1887.

Application filed May 9, 1887. Serial No. 237,650. Term of patent 7 years.

To all whom it may concern:

Be it known that I, JOHN HARDMAN, of the city and county of New York, in the State of New York, have originated and produced a new Design for Ornamental Panels, of which the following is a description.

My design is for a panel which may be used as a distinctive part of a piano-forte case or other piece of cabinet-work; and the design 10 consists of a central rectangular plain portion, a surrounding ornamental portion, and an outer plain border portion, the edges of which form a straight and plain sided rectangular figure, as hereinafter described, and shown in 15 the drawings.

In the accompanying drawings, Figure 1 is a face view of an ornamental panel embodying my design, and Fig. 2 is a transverse section thereof upon the plane indicated by the 20 dotted line $x x$, Fig. 1.

Similar letters of reference designate corresponding parts in both figures.

The ornamental panel which embodies my design, and which may be of slight thickness, 25 as shown in Fig. 2, is composed of a central

portion, A, which is rectangular and has a plain surface, a surrounding ornamental border portion, B, here represented as made up of a series of scrolls, b , and an outer plain border portion, C, also rectangular, and the 30 margins of which constitute a straight and plain sided rectangular figure. The ornamental portion B surrounds the central plain portion, and is in turn surrounded by the plain border C, the edges of which constitute the straight 35 side of the rectangular figure.

What I claim as my design, and desire to secure by Letters Patent, is—

The design for an ornamental panel, consisting of a rectangular plain portion, A, the surrounding ornamental portion B, and the outer plain border portion C, the edges or margins 40 of which form a straight and plain sided rectangular figure, substantially as herein shown and described.

JOHN HARDMAN.
